UNITED STATES PATENT OFFICE.

WILLIAM LOREY, OF PHILADELPHIA, PENNSYLVANIA.

FILTER.

No. 877,206.

Specification of Letters Patent.

Patented Jan. 21, 1908.

Application filed April 4, 1907. Serial No. 366,417.

To all whom it may concern:

Be it known that I, WILLIAM LOREY, a citizen of the United States and resident of Philadelphia, in the county of Philadelphia and State of Pennsylvania, have invented 5 certain Improvements in Filters, of which the following is a specification.

The object of my invention is to produce a filter of improved construction which will 10 deliver a constant stream of filtered water and can at any time be readily cleansed and fresh filtering material readily introduced.

In the accompanying drawings, Figure 1 is 15 a general view of my improved filter in vertical section; Fig. 2 is an elevation of the left hand end as seen in Fig. 1, and Fig. 3 is a plan view with part broken away.

The hollow frame 4 is supported upon the hollow trunnions 5 and 6 turning in bearings 20 7, 8, and 9 which are supported by the fixed stands 10 and 11. A gear 12, fixed to the bearing 8, meshes with a pinion 13 mounted on a shaft 14 which is carried by the hollow frame 4. The other end of the shaft 14 25 carries a bevel pinion 15 which engages with a gear rack 16 attached to the filter casing 17. The casing is carried by and revoluble with the frame 4 in the hollow water-tight bearings 18, 19 and 20 in which its trunnions 18', 30 19' and 20' are journaled.

Upon the base 25 of the casing 17 are supported concentric cylinders 26, of porous stone or other suitable porous material, which are wrapped with wire 27 to strengthen 35 them. Sets of tubes 28 extend axially through the annular spaces 21 between the porous cylinders. These tubes connect at their lower ends with the passages 29 cored in the base 25 and are provided with the 40 openings 30 near the lower ends above which they are closed by plugs 22, communication between the annular spaces and the passages being effected by the openings. The spaces between the cylinders are covered at their 45 tops by annular caps 31 which fit upon adjacent cylinders. Sharp clean cut pebbles 66 are placed in the spaces and are preferably of tetrahedral form. The tubes 28 are provided near their upper ends with apertures 32 50 through which they open into the tops of the spaces 21 and below which they are closed by plugs 33. The tubes 28 extend upwardly through the annular caps 31 and communicate by openings 34' with a passage 34 which 55 communicates through the trunnion 18' and the hollow bearing 18 with the passage 4' in

the frame 4 and thence, by the passage 23 in the trunnion 6, the annular space 24', within which the trunnion revolves, and the passage 24 with the waste tank 40. The spaces 35, 60 36, and 37 adjacent to the cylinders communicate with each other by annular apertures 35', 36' and 37' at their tops and at their lower ends open by passages 35'', 36'' and 37'' into a passage 38 which communicates through the hollow bearing 19 with the passage 71 in the frame 4.

A motor 50 is operated by water from the tank 40 flowing through the pipe 51. The motor operates a shaft 52 carrying a worm 70 53 meshing with a worm wheel 54 which is journaled in a frame 55 and engages a vertical screw 56. This screw passes through the end of a chamber 57, being splined there- 75 in to prevent it from turning, and carries at its upper end a piston 58. The chamber 57 is filled with powdered charcoal, or other suitable filtering material 59, and connected at its upper end with the passage 60 for the raw water. When the motor 50 is operated 80 it gives the piston 58 a slow uniform upward movement, feeding the filtering material evenly and regularly to the incoming water flowing through the pipe 60 which communi- 85 cates with the passage 60' in the trunnion 6, thence by the passage 4' in the frame 4 to the hollow bearing 20, and thence by the passage 29 to and through the openings 30. When the filtering material is to be replaced 90 in the chamber 57, the frame 55 is removed by disconnecting its supporting bracket 62, and the part 57', clamped on the end of the chamber 57, is removed, carrying with it the screw and piston. The chamber 57 is then inverted by turning it about on the water 95 tight bearings 63 and its other end closed by means of the valve 64, when it can be refilled with filtering material and afterward re- placed in operative position and the valve 64 opened.

In the filtering operation the raw water, with the charcoal picked up from the chamber 57 flows through the passages 60, 60', 4'', 29 and 30 into the spaces 21 and filters through the porous cylinders 26 into the spaces 35, 105 36 and 37 whence it escapes by the passages 38 and 71, the clarified water being drawn off by the pipe 70. As the water passes through the porous cylinders, it deposits its contained filtering material on the walls of 110 the chambers 21 until these walls are coated sufficiently to form an efficient filter for the

succeeding water supply which percolates therethrough and is cleansed thereby.

The shaft 52 carries a bevel gear 80 which meshes with a similar bevel gear 81 on a journal shaft 82 supported by brackets 83 from the standard 11. The other end of the shaft 82 carries a worm 84 meshing with a worm wheel 85 which is secured to the hollow trunnion 6 of the filter casing.

10 When it is desired to clear the filter of the deposits of impure matter collected in the cylindrical spaces 21, the tank 40 is flushed and delivers water through the pipe 51 to the motor 50, the head being sufficient to rotate the motor. This, acting through the mechanism described, causes the frame 4 carrying the filter to revolve on its hollow trunnions 5 and 6, at the same time rotating the filter in the frame 4 through the gears 12 and 13, thus disturbing and dislodging the deposits of impure matter together with the soiled coating of filtering material in the spaces 21, which is carried off by the constant flow of water introduced through the passages 60', 4", 29 and 30 to the spaces 21. The water carrying this waste material finds an outlet from the spaces 21 only through the orifices 32 in the ends of the tube 28, whence it flows through the openings 34', the passage 34 and the hollow frame 4, through the passage 23 in the hollow trunnion 6 to the pipe 24 leading to the tank 40. The waste water is thus utilized to operate the motor and effect the succeeding cleansing operation. Simultaneously with the above operation the piston 58 is slowly forced upward in the chamber 57 feeding a predetermined amount of the filtering material 59 to the system for the recoating of the porous cylinders within the filter casing.

Having described my invention, I claim:

1. In a filter, a porous septum, a liquid conduit leading to said septum, a chamber containing a filtering material communicating with said conduit, a piston in said chamber, and means for moving said piston.
2. In a filter, a porous septum, a conduit leading thereto, a chamber containing filtering material communicating with said conduit, a piston movable in said chamber, a threaded rod for moving said piston, a wheel engaging and moving said threaded

rod, and a motor connected with and operating said wheel.

3. In a filter, a porous septum, a conduit leading thereto and a conduit leading therefrom, a chamber containing filtering material communicating with the conduit leading to said septum, a tank communicating with the conduit leading from said septum, a motor connected with said tank and operated by liquid discharged therefrom, and means operated by said motor for forcing filtering material into the conduit leading to said septum. 65

4. In a filter, a frame having passages therein and trunnions having passages therein, bearings in which said trunnions are journaled, a casing having hollow trunnions journaled in said frame and communicating with said passages, and one or more porous septa in said casing and disposed between the passages through said hollow trunnions. 70

5. In a filter, a frame having separate passages, trunnions fixed to said frame and having passages communicating with said frame passages, and a casing having trunnions journaled in said frame with passages communicating with the passages therein. 80

6. In a filter, a frame having journaled trunnions; a casing having trunnions journaled in said frame; one or more porous septa in said casing; a conduit extending through a frame trunnion, the frame and a casing trunnion to said septum or septa; a conduit extending from said septum or septa through one of said casing trunnions, said frame and one of said frame trunnions; and mechanism for revolving said frame 90 and casing. 85

7. In a filter, a frame having journaled trunnions, a casing having trunnions journaled in said frame, filtering devices in said casing, means for passing water to and from said casing, and gearing for simultaneously revolving said frame and casing. 95

In testimony whereof I have hereunto set my name this 30th day of March, 1907, in the presence of the subscribing witnesses. 100

WILLIAM LOREY.
